(57) **CLAIM**

The ornamental design for a combined portable chiller and dispensing unit, as shown and described.

DESCRIPTION

FIG. 1 is an isometric view of a combined portable chiller and dispensing unit;
FIG. 2 is a front view thereof;
FIG. 3 is a rear view thereof;
FIG. 4 is a left-hand side view thereof, wherein a right-hand side view is a mirror image of the left-hand side view;
FIG. 5 is a top view thereof; and,
FIG. 6 is a bottom view thereof.
